UNITED STATES PATENT OFFICE.

PHILIP A. MYERS, OF ASHLAND, OHIO, ASSIGNOR TO THE F. E. MYERS & BROTHER COMPANY, OF ASHLAND, OHIO, A CORPORATION OF OHIO.

POWER HEAD FOR OPERATING PISTON RODS OF PUMPS.

Application filed October 12, 1921. Serial No. 507,220.

To all whom it may concern:

Be it known that I, PHILIP A. MYERS, a citizen of the United States, residing at Ashland, in the county of Ashland and State of Ohio, have invented certain new and useful Improvements in Power Heads for Operating Piston Rods of Pumps, of which the following is a specification, reference being had therein to the accompanying drawing.

10 This invention relates to power heads for operating the piston rods of pumps, such as pumps that are used for drawing water from wells.

The object that I have in view is the provision of a casing adapted to contain a quantity of lubricant combined with operating mechanism carried within the casing and including a rotary-reciprocating or oscillating member a part of which is within the 15 casing and another part of which is outside of the casing, the part within being adapted for connection with the operating mechanism and the part without for connection with the pitmen which actuate the pump rod, the arrangement being such that this member is oscillated by the operating mechanism within the casing and in turn reciprocates the pitmen.

In the accompanying drawings:

30 Fig. 1 is a side elevation of a pump head and a partial elevation in sectional view of my improved power head;

Fig. 2 is a perspective view, in detail, of the oscillating actuating member;

35 Fig. 2^a is a similar view to Fig. 2 showing the arms separate from each other instead of integral as in Fig. 2;

Fig. 3 is a plan view with the cover of the 40 casing removed and the upper rigging of the pump head omitted;

Fig. 4 is a plan view of the apparatus showing a modification in the oscillating-actuating member and its relation to the casing; and,

45 Fig. 5 is a perspective view of such member in detail.

In the drawings, the numeral 1 designates a pump head of any kind, such as a pump head adapted to be mounted upon a pump 50 platform and having a spout 2, a handle 3 for operating the piston rod 4 and pitmen 5, one at either side, to actuate the pump rod when the handle is disconnected therefrom. These several features are common and in 55 general use. It is to operate the piston rod

and the pitmen that my invention is designed. It comprises a casing 6, preferably made of cast iron and forming within it a chamber for holding a suitable lubricant and the operating mechanism. This mechanism consists of a shaft 7 having bearings in the side walls of the casing and carrying an eccentric 8 and a gear wheel 9. The eccentric and gear wheel are within the casing and are adapted to dip into the oil to 60 effect their lubrication. A driving shaft 10 is also mounted in the casing and equipped with a pinion 11 which meshes with the gear wheel 9 and with a pulley wheel 12 adapted to receive a belt operated by power, such as 65 an electric motor or gasoline engine.

On the eccentric 8 is mounted an eccentric rod 13 which when the eccentric is rotated is given a generally reciprocating motion. This eccentric rod connects with my oscillating actuating member consisting of crank arms 14 and 15 set at an angle to each other, preferably a right angle, forming an integral casting as indicated in Fig. 2 and 70 mounted to oscillate on a shaft 16 having 75 bearings in the walls of the casing. Or, as indicated in Fig. 2^a, the arms 14 and 15 may be of separate pieces or castings and keyed to the shaft as shown at 16^a.

In either case when the eccentric rod is 80 operated it will impart a rotary reciprocating motion to the actuating member, the arm 14 of which is connected to the eccentric rod as indicated at 17 while each arm 15 is 85 connected to one of the pitmen 5, as indicated at 18. The latter connection is effected through the studs 19 that project from the arms 15, as will be clearly seen in 90 Figs. 2 and 3. The casing is slotted as seen at 20 to permit of the arms 15 having free 95 oscillating movement; while a removable cover 21 is provided for giving access to the interior of the casing.

In order to permit of the insertion and withdrawal of the shaft 10 and its pinion 15, with the pinion on the shaft, a bushing 22 in the nature of a bearing is used and 100 removably secured to the casing by screws or bolts 23. The exterior diameter of this bushing is slightly in excess of that of the 105 pinion so that the opening in the casing which is occupied by the bushing is large enough for the insertion and removal of the pinion, as indicated by dotted lines in Fig. 3.

Referring now to the modification shown 110

in Figure 4, it will be seen that the shaft 24, which otherwise corresponds with the shaft 16, is extended beyond and outside of the casing so that the arms 25 of the actuating member are outside of the casing throughout their length, while the arm 26 of such member is within the casing as in the other form. These arms are rigidly mounted on the shaft 24 in any convenient manner. As seen in Fig. 5, the relation of the arms 25 and 26 is the same as the relation between the arms 15 and 14 in the other form.

By reason of locating the arms 25 in the modified form, wholly outside of the casing, the casing need not be slotted as at 20 in the other form. This has the advantage of enabling me to use a greater quantity or depth of lubricant in the casing.

Referring now to the operation of my power head, it will be seen that when the eccentric is rotated by the gearing and belt pulley it will reciprocate the eccentric rod 13 which in turn will oscillate the actuating member. This motion of the actuator will reciprocate the pitmen and cause them to operate the pump rod 4 up and down.

It will also be noted that the travel of the actuating member is through a short arc or portion of a circle, and that this limited movement avoids throwing the pitmen materially out of the straight line, with the result that they lift essentially in a

vertical plane when acting on the piston rod, and thereby avoid side pressure or 35 thrusts on the rod.

I conceive myself to be the first to provide a rotary-reciprocating member in the nature of an actuator interposed between operating mechanism and pitmen adapted 40 to operate a pump rod, such actuating member traveling through a short arc and having its arms preferably at an angle to each other.

Having thus fully described my invention, what I claim as new and desire to secure by 45 Letters Patent, is:—

1. In a power head, the combination with a casing and power mechanism mounted therein, of an oscillating actuator supported by the casing and having an arm within the 50 casing connected to the operating mechanism, and a pair of arms outside of the casing adapted for connection with pitmen.

2. In a power head, the combination with a casing and a pinion, a gear wheel, an eccentric, and an eccentric rod within the casing, of an oscillating actuator comprising a shaft mounted within and extended beyond the casing, an arm on the shaft within the casing connected with the eccentric rod and a pair of arms on the shaft outside of the casing and adapted for connection with pitmen.

In testimony whereof I affix my signature.

PHILIP A. MYERS.
